(57) **CLAIM**

I claim the ornamental design for a set of two magnetically attractable interior and exterior components positionable on opposite sides of a curved upstanding sidewall of a non-

ferrous container for hanging a paint brush inside the container, as shown and described.

DESCRIPTION

FIG. 1 is a first perspective view showing my new design, with the view showing mainly front, top and right side features of the two components of the set;

FIG. 2 is a second perspective view of thereof, with the view showing mainly rear, bottom and left side features of the two components of the set;

FIG. 3 is a front view of the exterior component;

FIG. 4 is a rear view of thereof;

FIG. 5 is a top view of thereof;

FIG. 6 is a bottom view thereof;

FIG. 7 is a right side view thereof, it being understood that a left side view is identical hereto but a mirror reversal image thereof;

FIG. 8 is a front view of the interior component;

FIG. 9 is a rear view of thereof;

FIG. 10 is a top view of thereof;

FIG. 11 is a bottom view thereof;

FIG. 12 is a right side view thereof, it being understood that a left side view is identical hereto but a mirror reversal image thereof;

FIG. 13 is a perspective view identical to FIG. 1 showing the exterior and interior components spaced on opposite exterior and interior sides of a portion of a curved upstanding sidewall of a container that is depicted by broken lines which are provided only for illustrative purposes, and form no part of the claimed design; and,

FIG. 14 is a perspective view substantially identical to FIG. 13 except that the exterior and interior components have been moved into magnetically attractive engagement with the curved upstanding sidewall that is depicted by broken lines which are provided only for illustrative purposes, and form no part of the claimed design.

Features shown in broken lines are for illustrative purposes only, and form no part of the claimed design.

Any portions of the components of the set not shown form no part of the claimed design.
